UNITED STATES PATENT OFFICE.

FRANK S. RICHARDS, OF WARREN, PENNSYLVANIA

NURSING-BOTTLE STOPPER.

1,250,658.

Specification of Letters Patent. Patented Dec. 18, 1917.

Application filed August 1, 1916. Serial No. 112,506.

To all whom it may concern:

Be it known that I, FRANK S. RICHARDS, a citizen of the United States, and a resident of Warren, in the county of Warren and State of Pennsylvania, have invented certain new and useful Improvements in Nursing-Bottle Stoppers, of which the following is a specification.

My invention relates to the feeding of infants, and the main object thereof is to provide a strictly sanitary nursing bottle from the bottom of which the milk is drawn in feeding therefrom, thereby avoiding the necessity for tipping the bottle as with the conventional bottles now in use.

A further object is to provide a stopper, nipple, and suction tube in readily separable parts for individual cleansing, and a still further object is to provide said tube in two sections one of which is made of inexpensive material and intended to be thrown away after each use of the bottle.

My invention is fully described in the following specification, of which the accompanying drawings form a part, in which like characters refer to like parts in each of the views, and in which:—

Figure 1 is an elevation of a nursing bottle, partly broken away, and showing my attachment thereto in section;

Fig. 2 is a section taken on the line 2—2 of Fig. 1; and Fig. 3 is a detached view of one of the members of a suction tube which I employ.

Referring to the drawings, 4 represents a nursing bottle of any desired type, 5 a rubber stopper therefor, 6 a detachable flexible nipple thereon, 7 a funnel-shaped tube frictionally held in the stopper, and 8 a tube in frictional engagement with the lower end of the tube 7 and preferably extending to a point closely adjacent the bottom of the bottle.

The funnel-shaped tube 7 is formed of non-corrosive material, such as glass, aluminum, etc., and is readily removable from the stopper for cleansing, whereas the tube 8 is preferably made of waxed paper or other inexpensive material whereby a new one may be used at each bottle filling, the upper end of the tube 8 being shown as telescoped over the lower end of the tube 7, although

this might be reversed, and it will be noted that, in the form of construction shown, the bottom of the stopper is recessed to receive 55 the tube 8 and aid in holding the same in place.

When it is necessary to refill the bottle the stopper is withdrawn, the nipple removed therefrom, the tube 7 detached from 60 the stopper, and the tube 8 thrown away, the stopper, nipple, and funnel-shaped tube 7 being then scalded, the stopper again receiving the tube 7 and nipple and a new tube 8 being slipped into engagement with the tube 65 7, the said parts being assembled on and removed from the bottle as a unit.

The tube 7 is made funnel-shaped in order to insure its relative position with respect to the stopper upon being replaced after removal, and the tube 8 extends to a point 70 closely adjacent the bottom of the bottle so that the infant may feed from the bottle without the need of a nurse tipping the bottle so as to supply milk to the nipple. 75

My invention is thoroughly sanitary and, while I prefer to employ a destructible tube 8, I do not limit myself to such use, as a permanent though removable tube 8 could be employed, though causing trouble in 80 cleansing.

Having fully described my invention, what I claim as new, and desire to secure by Letters Patent, is:—

As a new article of manufacture, a nursing 85 bottle stopper, comprising a homogeneous rubber stopper provided with a longitudinal opening having a flaring outer end, the inner end of the opening being slightly enlarged, a tube having a funnel 90 shaped outer end and removably fitting in the opening of the stopper, a paper tube extending into the enlarged inner end of the opening of the stopper and into which the inner end of the funnel shaped tube extends, 95 said paper tube being of a length to extend within a short distance of the bottom of the bottle with which the stopper is used, and a nipple removably secured to the stopper.

FRANK S. RICHARDS.
